BRAKE

Harry C. Liveringhouse, Providence, R. I., assignor to United States Rubber Company, New York, N. Y., a corporation of New Jersey

Application February 13, 1940, Serial No. 318,677

5 Claims. (Cl. 57—16)

This invention relates to improvements in braking mechanisms for core covering machines. In the Getchell Patent No. 1,970,228 for Core covering machines there is shown, described and claimed brake mechanism associated with the hollow spindle of a core covering unit, and adapted to bring the spindle to rest quickly when the current to its operating motor is cut off. The brake mechanism disclosed by this patent comprises a brake disc 46 secured to the lower end of the hollow spindle in spaced relation to its operating motor, and there is slidably mounted about the hollow spindle between the disc 46 and the lower end of the motor casing a brake actuating collar 58 which is continuously urged by a coiled spring 64 towards the brake applying position. During the normal running operation the collar 58 is held raised in its inoperative position by a lever 51 which is pivotally mounted upon a projection 54 extending down from the motor casing 29.

This covering machine of the Getchell patent is a good practical construction and has been used for years to produce large quantities of elastic yarn. Recently, however, steps have been taken to increase the speed at which the hollow covering spindles of the Getchell machine are operated, to thereby operate these spindles at a speed of 14,000 R. P. M. or higher. It is found in practice that the vibration imparted to the motor casing 29 by this increased speed and to the brake mechanism supported from the motor casing causes excessive wear of the braking parts.

The present invention, therefore, contemplates improved braking mechanisms over that of the Getchell patent whereby the braking parts are relieved from the objectionable vibrations of the motor that operates the hollow covering spindle.

In the Getchell patent there is disclosed a vertically sliding rod 146 adapted to be manually operated to control the covering operation. The primary feature of the present invention resides in a novel construction whereby one of the braking elements is supported by this vertically sliding rod entirely independently of said motor for movement into and out of engagement with the other braking element secured to the hollow spindle of the operating motor.

A further feature of the present invention resides in means for yieldingly and rockingly supporting the braking element carried by said manually operated rod, and in means for normally holding this braking element in approximately

parallel relation with the rotating braking element.

The above and other features of the invention and novel combination of parts will be herein-after described in connection with the accompanying drawing which illustrates one good practical form thereof.

In the drawing:

Fig. 1 is a vertical sectional view through a core covering machine provided with the braking mechanism of the present invention, the brake being shown in the off position.

Fig. 2 on a larger scale is a top plan view of that portion of the braking mechanism which is supported below and independently of the operating motor; and

Fig. 3 is a sectional view taken on the line 3—3 of Fig. 1, the brake being shown in the on position.

The braking mechanism of the present invention may be employed upon various types of core covering machines and in the construction shown only one core covering unit is illustrated, but the frame and core being covered are shown as broken away, as it is contemplated that a second covering unit may be employed below the first as shown in the Getchell patent above cited.

The machine illustrated has the upright end frame 10 to which are secured the horizontally extending rails 11 and 12. The rail 11 has secured thereto an electric motor 13 provided with a rotor 14 which is mounted upon and drives the hollow spindle 15 through which spindle the core 16 to be covered passes. This spindle 15 in the construction shown is provided at its lower end with a brake disc 17, and upon the portion of the spindle 17 that projects upwardly some distance above the motor is mounted the yarn supply package 18 which package rotates in an opening formed in the plate 19 that is supported from the rail 11 by the upright 20. Upon the plate 19 is mounted the usual ring 21 and traveler 22 through which the covering yarn 23 passes as it unwinds from the package 18 and is wound about the core 16 by the rotation of the yarn package 18 and supporting spindle 15. Above the upper end of the spindle 15 is supported a guide 24, through which the covered core passes in an upward direction towards the take-up mechanism to be described.

The present invention is well adapted for use on covering machines adapted to cover wire, rubber thread or other types of cores, but the core let-off and take-up mechanism shown has been designed more particularly for use in core cover-

ing machines for covering rubber thread where it is important to control the stretch of the rubber thread while the cover is being wound thereupon.

In the construction shown the core 16 to be covered is led upwardly from a supply spool 25 adapted to rest upon and be rotated in the unwinding direction by the power driven cork roll 26. The arrangement is such that the spool 25 will be rotated at a uniform peripheral speed irrespective of the amount of core thread wound thereupon. This spool is held in place upon the driving roll 26 by a bifurcated bracket 27 having the slotted portions 28 adapted to receive trunnions upon the spool 25 and to support the spool 15 so that it may be moved into and out of engagement with the driving roll 26 as more clearly set forth in the Cobb Patent No. 1,976,328, for Apparatus for making elastic yarns.

The covering machine illustrated in the drawing appears to be provided with only one covering motor 13 but it will be understood that this machine may be provided with a large number of these covering units arranged side by side lengthwise of the rail 11. It is therefore desirable to provide mechanisms whereby the operator may start or stop the operation of any one covering unit without disturbing the other units. To this end each covering unit may be provided with manually controlled mechanism for starting and stopping the travel of the core upwardly through the covering spindle and for starting and stopping the rotation of the hollow spindle, as more fully set forth in the two patents above cited.

35 In the construction shown the covered core upon leaving the guide 24 passes around the lower nip roll 29 and between it and the upper nip roll 30. It then passes upwardly through a guide eye on the traverse mechanism 31 and then to a take-up spool or reel such as 32. The nip rolls 29 and 30 are rotated by the power driven roll 33 and the take-up roll 32 rests upon and is driven by the power driven roll 34. The nip rolls 29 and 30 are held in operative relation with each other by the bifurcated bracket 35, and the takeup spool 32 is similarly supported by a bifurcated bracket 36.

It should be noted that the brackets 27, 35 and 36 are all secured to a manually operable vertically sliding rod 37 so that this rod when moved upwardly from the position in which it is shown in Fig. 1, by the operating handle 38, will raise the let-off spool 25, the nip rolls 29 and 30 and the take-up spool 32 all out of engagement with their respective driving rolls to thereby arrest the upward feed of the core 16. The operating lever 38 is pivotally supported between its ends at 39 from the rail 11, and has the end 40 which is operatively connected with the sliding rod 37. The movement of the lever 38 to raise the rod 37 and stop the covering operation may serve also to operate an electric switch 41 to thereby cut off the driving current to the motor 13.

65 It is desirable to stop quickly the rotation of the spindle 15 after the driving current for the motor 13 has been cut off, and to this end the braking mechanism which will now be described has been provided. The hollow spindle 15, as above stated, has rigidly secured adjacent its lower end the brake disc 17 which may be formed of metal.

In accordance with the present invention the braking element which cooperates with the brake disc 17 is supported by the sliding rod 37 inde-

pendently of the motor 13 so that during the normal operation of this motor the motor vibrations will not be imparted to such braking element. To this end in the construction shown, there is mounted upon the rod 37, a bracket 42. 5 This bracket preferably has a flat upper surface and a clamping bolt 43 whereby a resilient supporting arm for the braking element may be adjustably secured to this bracket. The braking element is shown as comprising the brake plate 10 44 which may be stamped out of sheet metal and has secured to its upper face a cork washer or disc 45 adapted to frictionally engage the braking disc 17. The brake plate 44 is shown as having the downwardly extending ears 46 15 adapted to rockingly receive trunnions 47 formed at the outer ends of the looped spring arm 48 which yieldingly supports the brake element and is clamped to the bracket 42 by the bolt 43. The purpose in pivotally supporting the brake plate 20 44 is to cause its cork surface 45 to butt firmly against the brake disc 17. It is desirable, however, to provide means for holding this braking element in substantially parallel relation with the brake disc 17 when the brake parts are out of engagement with each other as shown in Fig. 1. This is accomplished in the construction shown by providing the coiled spring 49, one end of which is secured to an edge of the brake plate 30 44 while its other end is secured to a projection 50 upon the bracket 42.

It is found in practice that when the braking element 44 and associated parts are supported as herein contemplated so that they are not subjected to the vibrations of the running motor 13 they will give much better service than when subjected to such vibrations as in the construction of the Getchell patent above cited. Furthermore, the construction of the present invention is simple and inexpensive to manufacture and the sliding movement of the manually operative rod 37 serves in a highly satisfactory manner to apply the brake when this rod is raised to stop the rotation of the motor and feed of the core, and to relieve the brake when this rod is lowered to start the winding operation.

Having thus described my invention, what I claim and desire to protect by Letters Patent is:

1. In a core covering machine, in combination, 50 a hollow spindle, means for advancing a core to be covered through said spindle, an electric motor for winding a cover upon said core and provided with a rotor mounted on said spindle to rotate it, a brake disc secured to said spindle, a manually operable sliding rod adjacent said motor and operable to control the covering operation, a spring arm projecting laterally from said rod, and a brake element supported by said arm independently of said motor and adapted to be moved by 55 said rod into and out of braking engagement with said disc, whereby said arm and element are relieved from the motor vibrations.

2. In a core covering machine, in combination, 65 a hollow spindle, means for advancing a core to be covered through said spindle, an electric motor for winding a cover upon said core and provided with a rotor mounted on said spindle to rotate it, a brake disc secured to said spindle, a manually operable sliding rod adjacent said motor for controlling the covering operation, a spring arm projecting laterally from said rod, and a brake element pivotally supported by said arm independently of said motor for movement 70 by said arm into and out of braking engagement 75

with said disc, whereby said element is relieved from the motor vibrations.

3. In a core covering machine, in combination, a hollow spindle, means for advancing a core to be covered through said spindle, an electric motor for winding a cover upon said core and provided with a rotor mounted on said spindle to rotate it, a brake disc secured to said spindle, a manually operable sliding rod adjacent said motor for controlling the covering operation, an arm projecting laterally from said rod, and a brake element supported by said arm independently of said motor and adapted to be moved by said rod into and out of braking engagement with said disc, whereby said element is relieved from the motor vibrations.

4. In a core covering machine, in combination, a hollow spindle, means for advancing a core to be covered through said spindle, an electric motor for winding a cover upon said core and provided with a rotor mounted on said spindle to rotate it, a brake disc secured to said spindle, a manually operable sliding rod adjacent said mo-

tor for controlling the covering operation, a spring arm projecting laterally from said rod, a brake element pivotally supported by said arm independently of said motor for movement by said arm into and out of braking engagement with said disc, and a spring for yieldingly holding said pivoted element substantially parallel to said disc.

5. In a core covering machine, in combination, a hollow spindle supported in an upright position, means for advancing a core to be covered through said spindle, an electric motor for winding a cover upon said core and provided with a rotor mounted on said spindle to rotate it, a brake disc secured to the lower end of said spindle, a manually operable rod mounted for vertical movement to control the covering operation, a spring arm projecting laterally from said rod, and a brake element supported by said arm below said disc and independently of said motor and adapted to be raised into frictional engagement with said disc as said rod is raised to stop the covering operation.

HARRY C. LIVERINGHOUSE.
